CLAIM

The ornamental design for a noise muffler, as shown and described.

DESCRIPTION

FIG. 1 is a perspective exploded view of a noise muffler, showing our new design;
FIG. 2 is a right side view of the noise muffler of FIG. 1;
FIG. 3 is a left side view of the noise muffler of FIG. 1;
FIG. 4 is a bottom view of the noise muffler of FIG. 1;
FIG. 5 is a top view of the noise muffler of FIG. 1;
FIG. 6 is a front view of the noise muffler of FIG. 1; and,
FIG. 7 is a rear view of the noise muffler of FIG. 1.
The broken lines in the figures illustrate the portions of the design that form no part of the claimed design.
